UNITED STATES PATENT OFFICE

SAMUEL I. BERGER, OF NEWARK, NEW JERSEY

DESIGN FOR A CHARACTER FIGURE GROUP TOY

Application filed March 5, 1931. Serial No. 38,946. Term of patent 14 years.

To all whom it may concern:

Be it known that I, SAMUEL I. BERGER, a citizen of the United States, and residing at Newark, in the county of Essex and State of New Jersey, have invented a new, original, and ornamental Design for Character Figure Group Toy, of which the following is a specification, reference being had to the accompanying drawing, forming part thereof.

The figure is a perspective view of the character figure group toy.

The piano, chairs and character figures shown in the design, are physically attached to form a single structure.

I claim:

The ornamental design for a character figure group toy as shown and described.

SAMUEL I. BERGER.
